DESIGN FOR A CIGARETTE TRAY

Charles E. McCormick, Dearborn, Mich.

Application October 11, 1941, Serial No. 103,734

Term of patent 7 years

(Cl. 85—2)

To all whom it may concern:

Be it known that I, Charles E. McCormick, a citizen of the United States, residing at Dearborn, in the county of Wayne and State of Michigan, have invented a new, original, and ornamental Design for a Cigarette Tray, of which the following is a specification, reference being had to the accompanying drawing, forming part thereof.

In the drawing:

Fig. 1 is a front perspective view of a cigarette tray showing my new design;

Fig. 2 is a bottom plan view; and

Fig. 3 is a rear elevational view thereof.

I claim:

The ornamental design for a cigarette tray, as shown.

CHARLES E. McCORMICK.
